O. J. WALINSKY
LUGGAGE LOCKING DEVICE

Filed Dec. 7, 1925

Ossip Joseph Walinsky
INVENTOR.

BY Kenyon & Kenyon
his ATTORNEYS.

UNITED STATES PATENT OFFICE.

OSSIP JOSEPH WALINSKY, OF NEW YORK, N. Y., ASSIGNEE TO WHITE LUGGAGE CO. INC., OF NEW YORK, N. Y., A CORPORATION OF NEW YORK.

LUGGAGE-LOCKING DEVICE.

Application filed December 7, 1925. Serial No. 73,605.

This invention relates to luggage locking devices and is particularly applicable to luggage having an extended opening with a row of closure members on each side of the opening adapted to be forced into and out of meshed relation to each other by the action of a member slideable in the direction of the length of the opening and in either direction.

An object of this invention is to provide a simple and efficient arrangement for locking the closure apparatus of a receptacle in a desired position.

A more comprehensive understanding of the features of this invention can be obtained by reference to the accompanying drawings illustrating a preferred embodiment of the same.

Fig. 1 is a plan view of a receptacle showing the application of the invention thereto.

Fig. 2 is an enlarged end view of the same receptacle showing the locking device in closed position.

Fig. 3 is an enlarged detailed view of the same device in open position, and

Fig. 4 is an enlarged detail view of a modified form of the invention.

Referring now to the drawings, 10 represents a receptacle or piece of luggage which may be of any conventional size or shape and which is supplied with the customary handles 11. Extending laterally across the top of the receptacle 10 is an opening 12 in each edge of which is secured a row of gripping members 13. The inner extremities of all of the members of one of the rows 13 are inclined at a slight angle so that when forced between oppositely arranged members they will be held firmly thereby. The usual slide actuator 14 is supplied for alternately forcing the members into and out of engagement with each other for closing and opening the receptacle respectively. Inasmuch as this type of closure apparatus is well known in the art no specific claim is made thereto.

Riveted or otherwise secured to the receptacle 10 adjacent to one end of the opening 12 is a snap or spring lock 15 having an opening 16 in the face thereof, in the rear of which is a spring elevated bolt 17. The usual bolt actuator 18 is adapted to with-

draw the bolt from the position shown in the drawings and is provided with a slot for the insertion of a suitable key for locking the bolt in its extended position.

For causing a lateral movement of the slide actuator 14 from end to end of opening 12 and for locking the actuator in the position in which the gripping members are enmeshed, a hasp 19 having one end bent and pierced by an elongated slot is secured to the member 14 by a ring 20. The other end of the hasp is bent in such a manner as to permit its introduction into the slot 16 of lock 15 and is provided with a slot 21 for the reception of bolt 17.

Thus it will be seen that the hasp 19 serves a double purpose, namely, as the means for causing the lateral movement of the sliding member 14 for both opening and closing the receptacle, and as a contributory means for locking the receptacle in closed position.

In the modification shown in Fig. 4 the members 13', 14' and 20' are similar to the members 13, 14 and 20 of the other figures. A spring lock 25 is secured to the receptacle 10' in a position corresponding to that of lock 15. One end of a hasp 19' is fastened to the element 14' in a manner similar to hasp 19 but the other end of hasp 19' is provided with a recess 26 and a guard 27. The portion of the hasp containing the recess is adapted to be inserted in an opening 28 of the lock 25 and the recess in that position is engaged by a bolt not shown. Knob 29 movable laterally across the face of the lock is connected with the bolt to release the hasp at a desired time. The usual key slot is provided for the insertion of a suitable key to lock the bolt in the position in which it engages the slot 26 of the hasp. The operation of the other parts of this modification is similar to that of similar parts of the other figures.

It is to be understood that the present invention is not to be limited by the scope of the illustrated embodiment, but is to be limited only by such structures as may come within the scope of the appended claim.

What I claim and desire to secure by Letters Patent of the United States is:—

The combination with a receptacle having an expanded opening, of means for closing said opening including a member slidably laterally across said opening, a lock secured to said receptacle adjacent to one end of said opening, and a hasp movably secured to said member whereby said member may be moved

across said opening and being engageable with said lock to prevent movement of said member.

In testimony whereof, I have signed my name to this specification.

OSSIP JOSEPH WALINSKY.
